UNITED STATES PATENT OFFICE

GEORGE GODDU, OF WINCHESTER, MASSACHUSETTS, ASSIGNOR TO UNITED SHOE MANUFACTURING CORPORATION, OF PATERSON, NEW JERSEY, A CORPORATION OF NEW JERSEY

TACK-PULLING MACHINE

Application filed April 19, 1926. Serial No. 102,965.

This invention relates to tack-pulling machines and is illustrated as embodied in a machine for pulling temporary lasting tacks from boots and shoes.

5 In the manufacture of a welt shoe for example, before the welt is attached to the shoe by the welt sewing machine, it is the general practice to remove the lasting tacks which are inserted around the shank and forepart during the lasting operation to hold the upper in 10 lasted position, in order to avoid breakage of the tacks and to avoid breaking welt sewing machine needles or thread. To facilitate this tack pulling operation, the lasting tacks 15 around the shank and forepart of a welt shoe are only partially inserted. These tacks are, however, driven in a row, and the several tacks are positioned relatively close to one another. Tack-pulling machines are frequently constructed 20 with cooperating jaws arranged to grasp a tack and to pull it from the shoe as the latter is held against a work support. With such machines trouble has been experienced because in the rapid operation of the machine 25 it has been impossible wholly to protect the upper from damage by the jaws and also to prevent one of the jaws from occasionally engaging an approaching tack in the row and tending to drive the shoe away from the work 30 support as it is held against the support by the operator. This is objectionable to the operator and reduces the efficiency of the machine by retarding the speed of operation.

35 An object of the present invention is to provide an improved tack pulling machine which will be so organized as to obviate the difficulties above referred to and which in this and other respects will be more accurate in operation, have greater output capacity, and in the 40 use of which wear and tear will be minimized.

To this end, in accordance with a feature of the invention, the illustrated machine is provided with pointed, tack pulling tools and is 45 arranged to move the tools laterally of a row of tacks in a boot or shoe to insert the pointed end of one of the tools between successive tacks and then to move it away from the work in withdrawing a tack. As illustrated tools 50 are moved inwardly in converging directions over a portion of the bottom of a shoe to grip a

tack and then in another direction angularly related to said first movement and away from the shoe to pull the tack. As a result the machine is adapted to withdraw the temporary lasting tacks rapidly from the boot or shoe, 55 even though these tacks are close together in the row, and the danger of damage to the upper by the movable tools and of accidental gripping of the upturned edge of the upper by these tools is minimized. Besides this the disposition of the parts is such that the operator is given a full view of the work.

To assist the rapid presentation of the tacks in a row to the operation of the machine, in accordance with another feature of the invention, the illustrated machine is provided with a work support or rest in which there is a wide notch having angularly related edges with one of the edges arranged at an angle to the direction of movement of the tacks as they are presented to the machine and serving as a tack locating abutment. The improved operation of the machine whereby its speed is increased and the danger of interference between the operating tools and approaching tacks is minimized results to a large extent from the relation of the tack-pulling tools to this notch and especially to the tack-locating abutment thereof. In the illustrated machine 70 the pulling tools are provided with substantially parallel faces and are movable outwardly over the work support in converging directions and then upwardly away from the work support to pull a tack. One of the tools moves over a solid portion of the work rest and has its operative face substantially parallel to the length of its supporting lever and arranged to be superposed above the tack locating abutment as it approaches a tack to be pulled. There is therefore no possibility of the engagement of approaching tacks in this tool 80 until they are located against the abutment and ready to be pulled. The other cooperating tool has its operative face at an angle to the length of its supporting lever and moves in a direction making an acute angle with the tack locating abutment across the other edge of the notch to a position behind the shank of the tack located against said abutment so that, 85 in cooperation with the other tool, it grips a 90 95 100

tack positioned there. This provides a maximum freedom from interference between approaching tacks and the tool and allows a rapid presentation of successive tacks to the locating abutment at any angle within a wide range. Both tools are then moved in a direction angularly related to the direction of gripping movement away from the work rest to withdraw the tack.

Still another feature of the invention resides in the disposition of the moving parts of the machine so that sufficient lubrication of the parts is assured. In the illustrated construction the frame of the machine comprises an open topped receptacle which may contain oil, and the moving parts of the machine are mounted upon a cover for this receptacle so that they are disposed within the receptacle and are bathed in oil during the operation of the machine. The tool carrying members pass forwardly through a curved, hollow horn-shaped projection or neck formed integrally with the cover above its level, thus avoiding the transfer of oil from the receptacle to a point where it might be thrown upon the work.

In accordance with other features of the invention, the illustrated work or shoe support or rest is pivotally mounted and is rigidly held against upward movement but resiliently held against downward movement. Damage to the machine is thus avoided in case a tack becomes wedged between the pulling jaws and the work support. A depending, adjustably mounted finger is also provided adjacent to the end of the work support which may be brought into engagement with the upstanding edge of the upper to assist in guiding the work and, as illustrated, a deflecting member adapted to turn the edge of the upper out of the path of the pulling tools is adjustably mounted upon this finger.

These and other features of the invention will now be described with reference to the accompanying drawings in which:

Fig. 1 is a side elevation of the machine with parts broken away;

Fig. 2 is a detail view of the slidable support upon which the tool carrying levers are pivoted;

Fig. 3 is a fragmentary side elevation of the tools and work support viewed from the rear side as regards the direction of movement of the work;

Fig. 4 is a plan view of the machine with parts broken away and in section; and

Fig. 5 is a perspective view of the work rest and the tack pulling tools, showing them in the position which they assume after they have started to pull a tack, this view being taken in the opposite direction from that of Fig. 3.

The shape of the work or shoe support or rest 9 and the tack pulling tools 10 and 11 may best be seen from an inspection of Figs.

4 and 5, from which it will be seen that the outer end of the work rest 9 comprises a substantially flat plate 12 having a notched recess 14 the sides of which are substantially at right angles to form a wide throat for the admission of the successive tacks of a row. The rear edge of the plate 12, viewed as in Fig. 5, is curved to avoid interference with the work, and for a similar reason one corner is bent to form an upturned lip 16 to avoid any tendency toward disfigurement of the upper and further to allow tipping movement of the work so that the pulling tools may be brought into close relation to the upper 20. This will allow the center ends of the tools to be brought beneath the head of a deeply driven tack, the head of which projects only slightly from the work. In lasting a welt shoe such as the shoe illustrated in Figs. 3 and 5, the upper 20 has been pulled tightly over the last 22 and the feather 23 of the insole 28 with its upturned edge 24 in engagement with the outer lip 26 of the insole 28 and has been secured in lasted position by means of temporary lasting tacks 30. To assist the operator, when the work is presented to the machine, in guiding these tacks into the tack pulling position, as determined by the notch 14, a depending wedge shaped finger 32 is adjustably mounted and held by means of a screw 34 upon an arm 36. This finger is intended to be brought into the angle formed by the upturned edge of the upper 20 as it rests against the feather 23 and the lip 26, and in order to prevent any interference between said upturned edge 24 and the operating tools, a deflector 38 is adjustably mounted upon the lower end of the finger 32. The forwardly extending edge 40 of the notch 14 serves as an abutment against which successive tacks are located as they are positioned in the notch.

It will be observed from Fig. 5 that the outer ends of the tack pulling tools 10 and 11 are curved downwardly and inwardly to form jaws 41 and 43, respectively, which have their operative edges substantially parallel, as shown in Fig. 4. From Fig. 4 it may be also seen that the outer ends of the jaws 41 and 43 are pointed and that their cooperating tack engaging edges are substantially parallel to the forwardly extending tack locating edge 40 of the notch 14 in the work support 9. The tack pulling tools 10 and 11 are adjustably mounted by means of suitable clamps 42 and 44 upon the outer end of converging levers 46 and 48, which are slidably mounted between suitable guides, to be hereinafter described, for movement in converging planes, and it will be observed that the operative tack engaging edge of the tack pulling tool 11 extends in a direction parallel to the length of its supporting lever 48 and parallel to the abutment edge 40, while the corresponding edge of the tack pulling tool 10 is angularly related to its supporting lever 46.

By means of this disposition of the parts the freedom with which successive tacks upon a shoe may be presented to action of the machine is greatly increased partly because of the wide notch 14 in the work support to which the tacks may be guided at various angles and partly because of the fact that the tacks may be presented at substantially any point along the length of the abutment face 40 forming one side of said notch. It is thus immaterial whether the tacks have been driven in a regular row along the edge of the shoe or whether they happen to be positioned at various distances from the lip of the insole and hence from the angle in which the guiding finger 32 is received because the machine will operate properly regardless of the part of the abutment 40 at which a tack is presented. Another factor which aids in the free presentation of tacks to the machine and the assurance that they will be readily pulled from the work arises out of the disposition of the operative edges of the tack pulling tools with respect to one another and the abutment edge 40. It will be observed from Fig. 4 that the movement of the jaw 43 of the tack pulling tool 11 is wholly over a solid portion of the work rest and that the operative edge of said jaw, being parallel to the length of the tool and at the same time to the abutment edge 40, moves outwardly over the work rest into a position where its operative edge is substantially coincident with the operative edge of the abutment. There can, therefore, be no interference between said jaw and the approaching tacks, and the angle of presentation of the row of tacks is independent of the operation of the jaw. The jaw 41 of the tool 10, on the other hand, while it is bound to move from a position outside of the row of tacks into a position intersecting said row in order that its operative face may be brought from the rear into contact with the shank of a tack located against the face of the abutment 40, has a movement, by reason of its guidance in a converging plane with respect to the other parts of the machine such that the operative face of the jaw 41 occupies an infinite number of successive positions in planes parallel to one another and to the operative face of the jaw 43 of the tool 11 up to the gripping position, with the minimum of interference between the approaching tacks and the jaw 41. Sometimes it is required to pull the temporary lasting tacks without disturbing the anchor tacks holding the toe wire, and it frequently happens that a group of tacks is found in close juxtaposition to one or the other of said anchor tacks. The withdrawal of the tacks of such a group without disturbing the anchor tack is greatly facilitated by the pointed end of the jaw 41 and its manner of movement with respect to the abutment face 40. Thus if it is necessary to withdraw a tack which is spaced very close

to another tack, the tack to be withdrawn may be presented near the outer end of the abutment face 40 so that only the very point of the jaw 41 need be brought into position between two tacks, thus allowing an accurate selection of a particular tack to be withdrawn and a positive withdrawal of said tack regardless of the exact point on the length of the operative faces of the jaws between which the tack is gripped. 75

Adequate lubrication of the machine is provided by means comprising an oil containing receptacle 50, suitably supported as by means of a column 52. The moving parts of the machine are mounted upon the under side of a cover 54 bolted to said receptacle and dip thereto so that they are bathed in oil. The cover 54 has a transverse upstanding rib 56 (Fig. 1) provided with a bearing for a drive shaft 58 to which power may be supplied as by a pulley 60, and said shaft is connected to the working parts of the machine by a gear 62. This gear 62 meshes with a gear 64 mounted upon an operating shaft 66 carried in bearings formed in a depending rib 68 made integral with or otherwise secured to the under side of the cover 54. The bearings for the shaft 66 are completed by cap plates 70 (Fig. 2) bolted thereto. It will be observed that the cover 54 is provided with an upwardly extending pocket 72 (Figs. 1 and 4) designed to overlie the gear 62. 95

In order to provide guides for the levers 46 and 48, a V-shaped rib 74 is cast integral with the cover on the under side thereof and the outer faces of said rib may be suitably machined, as at 76 (Fig. 4), to provide converging bearing surfaces against which said levers 46 and 48 may slide. The outer bearing for said levers at their rear ends may be provided by depending plates 80 having inturned horizontally disposed flanges by means of which said plates are adjustably mounted on the cover as by bolts 82 passing through slots in the cover. Bearings for the outer tool-carrying ends of the converging levers are also provided by wedge-shaped blocks 84 adjustably secured to the forward end of a hollow horn-shaped projection 86 (Fig. 1) upon the cover by bolts 88 which pass through slots in said projection so that forward and backward movement is allowed to bring the wedges 84 into bearing relation with wear plates 90 (Fig. 4) upon the forward, outer faces of each of the levers 46 and 48. 110 Each of the levers comprises a substantially horizontally disposed, bifurcated portion 92 (Fig. 1) at its rear end and a forwardly extending, upwardly curved portion 94, which passes through the horn-shaped casing 86. 115 The horizontally disposed, bifurcated portions 92 are guided for movement in converging planes between the plates 80 and the surfaces 76 (Fig. 1), and the levers are pivotally mounted near their central portions upon 120 130

pins 96 (Figs. 1, 2 and 4) secured to a slide 98. This slide 98 (Figs. 2 and 4) is arranged for front to back movement in a plane bisecting the angle between the converging planes of the levers 46 and 48 and is supported upon horizontal rods 100 secured to the depending rib 68 on the cover 54. Reciprocation of this slide 98 is provided by a cam track 102 on the face of the gear 64 and a cooperating roller 104 mounted upon a detachable bracket 106 secured to the slide 98. The levers 46 and 48 are free to move laterally with respect to their pins 96, as will be seen to be necessary upon inspection of Fig. 4, in order that said levers may slide in converging planes angularly related to the plane of movement of the slide 98 upon which the pivot pins 96 are carried.

By this and other mechanism to be later described, the movement in a vertical plane of a point upon either of the operating tools follows a path indicated by dot and dash lines in Fig. 3 and will be seen to comprise a substantially horizontal forward movement 110 by which the cooperating, thin edges of the jaws of the tack pulling tools 10 and 11 are brought beneath the head of a tack as said tools move laterally from a position where they are outside of the line of tacks into a position intersecting the line of tacks. The tack pulling tools are next moved vertically, as at 112, to effect a tack pulling movement and are returned into position for a subsequent tack engaging and pulling movement over a curved path 114. It should be remembered that the forward horizontal movements 110 of the tools are in converging directions, bringing the parallel operating faces of said tools into gripping engagement with the sides of the shank of a tack, which relation is maintained during the vertical movement 112. After this, in their return movement 114, the tack pulling tools move in diverging directions and release the tack.

In order to impart this compound movement to the tack pulling tools, provision is made for tilting the levers 46 and 48 about the pivot pins 96 and to this end coacting bearing blocks 120 and 122 (Fig. 1) are received between the bifurcated ends 92 of said levers and are arranged to surround ball-shaped portions 124 (see Fig. 4), which are eccentrically formed upon the operating shaft 66, as indicated in dotted lines in Fig. 1, so that the combined action of said eccentric, ball-shaped portions 124, in tilting the levers 46 and 48, and of the cam operated slide 98 in moving the levers toward and away from the tacks is effective to produce the path of movement delineated in Fig. 3. It will be observed that the bearing blocks 120 and 122 may slide laterally with respect to the bifurcated ends 92, and provision is made for taking up wear between said blocks and the ends 92 of the levers by means of adjustable gib plates 126,

the position of which may be adjusted by means of screws 128 (Fig. 4).

Blocks 130 are bolted to the under side of the horn-shaped projection 86 of the cover 54, which provide a support for a transverse pin 132 upon which the work rest 9 is pivotally mounted, its upward movement being limited by bearing against a suitable portion of said blocks 130 as it is resiliently held in operative position by means of a spring 134 surrounding a stud 136. This prevents the possibility of breakage in case a tack should become jammed between the tools and the forward end of said work rest while at the same time providing a rigid support holding the shoe against upward movement as the tacks are withdrawn from the work.

The bracket 36 supporting the grinding finger 32 is adjustably mounted upon the upper side of this same horn-shaped portion 86 and is held in adjusted position by means of screws 140 which may also be utilized to clamp in position a guard 142 extending outwardly and downwardly and provided with slots within which the tack pulling tools operate. If desired, the screws 88, by means of which the wedge shaped bearing blocks 84 are held in adjusted position may also be utilized to hold a cover 144, a fragment of which is shown in Fig. 1, which is arranged to extend outwardly over the upper side of the operating parts at the front of the machine.

There is thus provided a construction by means of which a single operative shaft passing across the diverging ends of the tool carrying levers 46 and 48 is effective to tilt said levers and to move them forwardly and backwardly in converging planes to bring the tools beneath the head of the tack, to lift the tools to pull the tack, and then to return them to starting position with a simultaneous release of the tack. It should be observed that in this movement the edge of the tack pulling jaw 43 moves in a right line substantially parallel to the abutment edge 40 of the notch 14 in the work support and that the tool itself overlies a solid portion of said work support during substantially its whole path of movement. As a result, interference between this jaw and the tacks being presented by the operator is practically eliminated. A uniform and continuous forward movement of the work as the operator presents the shoe to the machine is provided and interference between the other tack pulling jaw 41 and the tacks is minimized because of the pointed formation of the forward end of said jaw, whereby, as it is moved substantially horizontally from a point without the line of tacks to a point intersecting said line, it is allowed to pass between successive tacks and substantially eliminates danger of driving tacks inwardly. In addition, the horizontally movement of the jaws, as they are brought into tack pulling position above the work rest 9,

avoids danger of damage to the upper of the shoe, the possible grasping of the upper by the jaws, and allows full vision of the work as the operator presents the tacks into the notch 5 14 of said work rest 9.

Having described the invention, what I claim as new and desire to secure by Letters Patent of the United States is:

1. A tack pulling machine for successively withdrawing tacks arranged in a row in a boot or shoe having, in combination, tack pulling means comprising a jaw the forward end of which is sharpened to a single point to facilitate its insertion between successive 10 closely spaced tacks in the row of tacks, and means for moving said jaw laterally of the row of tacks to insert said pointed end between successive tacks and then moving it away from the shoe in withdrawing a tack. 15 2. A machine for pulling tacks from boots and shoes having a work rest provided with a flat work-engaging portion, tack pulling means, and means for sliding said tack pulling means forward over the work rest in a 20 plane parallel to said work engaging portion to bring said means into engagement with a tack and for then moving said tack pulling means substantially perpendicularly to said plane to withdraw the tack from a piece 25 of work. 30 3. A machine for pulling tacks inserted through the upper and into the insole of a shoe in the angle between the feather and the lip or rib of the insole comprising tack pulling tools movable inwardly from positions 35 away from the shoe in converging directions in a plane substantially parallel to the plane of said feather to grip a tack and then in a direction angularly related to said feather 40 to pull the tack.

4. A machine for pulling tacks from boots and shoes having a work rest with a flat work engaging portion, tack pulling jaws, levers for supporting said jaws, and means for reciprocating said levers to move the jaws in a plane parallel to the flat portion of said work rest into engagement with a tack adjacent to said work rest and then oscillating the levers and jaws angularly to said rest to 45 withdraw the tack from the shoe. 50

5. A machine for pulling tacks from boots and shoes having, in combination, a work rest provided with a flat work-engaging portion having a straight-edged tack abutment, and tack-pulling means comprising a member having a straight-edged operative face substantially parallel to said abutment and movable in a plane parallel to said work-engagement portion into position to engage a tack 55 located against said abutment and movable at an angle to said abutment in pulling said tack. 60

6. A machine for pulling tacks from boots and shoes having a work rest provided with 65 a tack-locating notch one edge of which is

substantially at right angles to the direction of approach of tacks to said notch, tack-pulling means comprising a pointed tool having a tack-engaging edge substantially parallel to the named edge of said notch in the work rest, and means for moving said tool both outwardly over the work rest into position to engage a tack located against the edge of the notch and angularly thereto in withdrawing the tack. 70

7. A machine for pulling tacks from boots and shoes having a work rest provided with a tack locating notch one edge of which is approximately normal to the direction of approach of the tacks to said notch, tack pulling means comprising a tool having a sharp end forming a point with its tack engaging edge substantially parallel to said edge of the notch in the work rest, and means for moving said tool outwardly over the work rest to bring said tool behind and into engagement with a tack located in said notch and then away from the work rest in withdrawing the tack. 75

8. A machine for pulling tacks from boots and shoes comprising a substantially straight edged tack locating abutment, and tack pulling means comprising a tack pulling tool having a flat operative face movable into successive positions located in planes parallel to 90 said abutment in a direction forming an acute angle with said abutment to pass behind and engage a tack located against the abutment. 95

9. A machine for pulling tacks from boots and shoes comprising a work rest having a notch the edges of which are substantially at right angles, one edge of said notch serving as a tack locating abutment for tacks presented at any point throughout its length, tack pulling tools having jaws the edges of which may be brought together along the line of said abutment to grip a tack located thereagainst, and means for moving said jaws relatively to each other in converging directions into tack gripping position and then away from the work rest to pull a tack. 100 105

10. A machine for pulling tacks from boots and shoes comprising a work rest having a wide notch with angularly related edges one of which serves as a tack locating abutment, and tack pulling means comprising a tool movable in a direction making an acute angle with said abutment, the forward end of said tool being sharpened to a single point to facilitate its insertion between successive closely related tacks one of which is positioned against the abutment. 110 115

11. A machine for pulling lasting tacks from boots and shoes having a work rest provided with a tack locating abutment, and tack pulling means comprising a tool at the rear of said abutment and movable away from the abutment to assist in pulling a tack, and another tool movable inwardly forwardly of said abutment at an angle thereto along a 120 125 130

- plane extending at right angles to the abutment to grasp a tack located thereagainst and then away from the abutment to assist the other tool in pulling the tack.
- 5 12. A machine for pulling tacks from boots and shoes having cooperating tack pulling jaws, and levers for supporting said jaws disposed in angular relation and movable in one direction to engage a tack and movable angularly thereto to withdraw the tack, the face of one of said jaws being substantially parallel to the length of its supporting lever.
- 10 13. A machine for pulling tacks from boots and shoes having cooperating tack pulling jaws, and levers for supporting said jaws disposed in angular relation and movable in one direction to engage a tack and movable angularly thereto to withdraw the tack, the face of one of said jaws being angularly related to the length of its supporting lever.
- 15 14. A machine for pulling tacks from boots and shoes having, in combination, cooperating tack pulling jaws, levers for supporting said jaws disposed in converging planes, and means for moving said levers to cause converging movement of said jaws to grip the opposite sides of a tack and then to move the jaws in another direction to withdraw the tack from the work.
- 20 15. A machine for pulling tacks from boots and shoes having, in combination, cooperating tack pulling jaws, levers for supporting said jaws disposed in converging planes, and means for moving said levers to cause converging movement of said jaws to grip the opposite sides of a tack and then tilting said levers to move the jaws in another direction to withdraw the tack from the work.
- 25 16. A machine for pulling tacks from boots and shoes having, in combination, cooperating tack pulling jaws, said jaws having tapered ends forming tack engaging edges, and means for moving said jaws in the general direction of their edges to bring said edges beneath the head of a tack and then lifting the jaws to withdraw the tack.
- 30 17. A machine for pulling tacks from boots and shoes arranged to pull successively tacks arranged in a row in a shoe having, in combination, tapered tack pulling jaws provided with cooperating substantially parallel tack engaging edges, means for moving said jaws in one plane from points outside the line of tacks into positions intersecting the line of tacks to cause the jaws to engage opposite sides of a tack beneath its head, and means for then moving said jaws in another plane to pull the tack.
- 35 18. A machine for pulling tacks from boots and shoes having, in combination, a slideable support, an operating shaft, tack pulling tools, levers carrying said tack pulling tools and mounted on said slideable support upon pivots in the plane of the operating shaft, and means upon said shaft for re-
- ciprocating said support and for oscillating said levers around their pivots to cause the tools to engage a tack and withdraw it from the shoe.
- 40 19. A machine for pulling tacks from boots and shoes having, in combination, tack pulling tools, levers supporting said tools arranged in converging relation, a slideable support, diverging pivots upon said support for said levers, and means for sliding said support and oscillating said levers to engage a tack and to withdraw it from the shoe.
- 45 20. A machine for pulling tacks from boots and shoes having, in combination, tack pulling jaws, levers carrying said jaws arranged in converging relation, guides for said levers to maintain said relation, a slideable support, pivot bearings for said levers upon said support, a shaft extending transversely between the diverging ends of said levers, means on said shaft for sliding said support, and other means also located on the shaft engaging said levers to oscillate them about their pivots.
- 50 21. A machine for pulling tacks from boots and shoes having, in combination, converging levers provided with tack pulling tools at their adjacent ends, a slideable support provided with pivotal bearings for said levers, the diverging ends of said levers being bifurcated, an operating shaft extending transversely between the diverging ends of the levers and provided with eccentrics cooperating with the bifurcated ends of the levers to oscillate them about their pivots, and means for sliding said support.
- 55 22. A machine for pulling tacks from boots and shoes having, in combination, converging levers provided with tack pulling tools at their converging ends, guides for said levers arranged to guide said levers in converging planes, means for sliding said levers in said planes, an operating shaft extending transversely between the diverging ends of the levers, and means upon said shaft for oscillating said levers to cause them to withdraw a tack.
- 60 23. A machine for pulling tacks from boots and shoes having, in combination, converging levers provided with tack pulling tools and having bifurcated divergent ends, an operating shaft extending transversely of said levers and passing through said bifurcated ends, slideable bearing blocks in said bifurcated ends, and eccentrics on said shaft engaging said bearing blocks and arranged to oscillate said levers to cause them to withdraw a tack.
- 65 24. A machine for pulling tacks from boots and shoes having, in combination, converging levers provided with tack pulling tools and having bifurcated divergent ends, an operating shaft extending transversely of said levers and passing through said bifurcated ends, slideable bearing blocks in said bifurcated ends, and ball shaped eccentrics on said shaft engaging said bearing blocks and ar-

- ranged to oscillate said levers to cause them to withdraw a tack.
25. A machine for pulling tacks from boots and shoes having, in combination, a supporting receptacle, a cover secured to said receptacle and provided with an opening, a tool carrying arm movable through said opening, and operating mechanism for said arm movably secured to the under side of said cover.
- 10 26. A machine for pulling tacks from boots and shoes having a supporting receptacle, a cover secured to said receptacle, operating mechanism secured to the under side of said cover so that it will be contained within the receptacle, and an operating tool connected to said mechanism extending outwardly beyond the receptacle into a position for application to the shoe.
- 20 27. A machine for pulling tacks from boots and shoes having, in combination, a supporting receptacle, a cover secured to said receptacle having an upwardly extending rib provided with a bearing, a drive shaft in said bearing, said cover having also a downwardly extending rib provided with a bearing, an operating shaft in said bearing, means for connecting said shaft, means for enclosing said connecting means opening into said receptacle, operating parts movably mounted upon the under side of said cover and arranged in cooperative relation with said operating shaft, and a tool connected to said operating parts extending outwardly from the receptacle into a position for application to the shoe.
- 25 28. A machine for pulling tacks from boots and shoes having, in combination, a supporting receptacle, a cover secured to said receptacle, a drive shaft mounted upon the upper side of said cover, an operating shaft mounted upon the lower side of said cover, means for connecting said shafts, operating parts movably supported upon the under side of said cover and cooperating with said operating shaft, and a tool connected to said operating parts and extending outwardly from the receptacle into a position for application to the shoe.
- 30 29. A machine for pulling tacks from boots and shoes having, in combination, a supporting receptacle, a cover secured to said receptacle and having a hollow horn-shaped projection open at its outer end, operating mechanism movably secured to the under side of said cover, and a tool carrying member connected to said mechanism extending outwardly through said hollow horn-shaped projection.
- 35 30. A machine for pulling tacks from boots and shoes having, in combination, a supporting receptacle, a cover secured to said receptacle and provided with a hollow horn-shaped projection extending upwardly and outwardly therefrom in a generally horizontal direction, operating parts movably secured to the underside of said cover within the receptacle, a tool carrying member extending upwardly and outwardly through said hollow horn-shaped projection, and a tool mounted upon the outer end of said member in position for engagement with the shoe.
- 40 31. A machine for pulling tacks from boots and shoes having, in combination, a supporting receptacle, a cover secured to said receptacle and provided with angularly related downwardly extending guides, tool carrying members slidably mounted in working relation to said guides in converging relation to one another, cooperating tools carried upon the outer ends of said members, and means movably mounted upon the under side of said cover for moving said members to cause said tools to move through cooperating cycles.
- 45 32. A machine for pulling lasting tacks from boots and shoes having, in combination, a work rest having a flat portion, tack pulling means movably related to said work rest, and a guiding finger having its ends positioned adjacent to said work rest and extending approximately normal to the flat portion of said work rest in position to engage a shoe in the angle between the lip and the feather of the insole.
- 50 33. A machine for pulling lasting tacks from boots and shoes having, in combination, a work rest having a flat portion, tack pulling means operatively related to said work rest, a guide finger extending downwardly in a position adjacent to said work rest with its end approximately normal to the flat portion thereof to engage the shoe in the angle of the upper between the lip and the feather of the insole, and means adjustably mounted upon said finger arranged to deflect the upstanding edge of the upper adjacent to said guide finger out of the path of the pulling means.
- 55 34. A machine for pulling lasting tacks from boots and shoes having a shoe rest disposed in substantially horizontal position and provided near its outer end with a flat shoe engaging portion having a notch into which the successive tacks of a row may be guided, one edge of said notch being substantially at right angles to the direction of movement of the tacks of the row as they are presented to the machine to form an abutment therefor, and tack-pulling means comprising a tool movable substantially along a horizontal plane in a direction angularly related to said abutment in pulling a tack positioned against the abutment.
- 60 35. A machine for pulling lasting tacks from boots and shoes having, in combination, a shoe rest disposed in a substantially horizontal position, the outer end of said shoe rest being constructed and arranged to provide an edge forming an abutment against which the tacks may be presented, and cooperating tack pulling jaws movable in and out along a plane extending substantially in

the direction of the length of the shoe rest to engage and lift tacks located by said abutment.

36. A machine for pulling lasting tacks from boots and shoes having, in combination, a shoe rest disposed in a substantially horizontal position, the outer end of said shoe rest being constructed and arranged to provide an edge forming an abutment against which tacks may be presented, cooperating tack pulling members movable in and out in the direction of the length of the shoe rest to engage and lift tacks located by said abutment, and means rigidly supporting said shoe rest against upward movement constructed and arranged to permit yielding downward movement so as to prevent breakage in case a tack becomes jammed between the tack-pulling members and the shoe rest.
37. A machine for pulling lasting tacks from boots and shoes comprising, in combination, a shoe rest having tack locating means, cooperating tack pulling tools movable outwardly over said shoe rest to engage a tack located by said means and away from the shoe rest to withdraw the tack from the shoe, and means for supporting said shoe rest constructed and arranged to hold it rigidly against movement away from the shoe and to allow it to yield in another direction away from the tools to release a tack accidentally caught between the tools and the rest.
38. A machine for pulling lasting tacks from boots and shoes comprising, in combination, a shoe rest provided with tack locating means, tack pulling means movable to traverse the shoe rest to engage a tack positioned by the locating means and then movable to withdraw it from the shoe, and means for holding the shoe rest rigidly against movement with the pulling means during the latter movement and to permit it to yield in another direction to free a tack accidentally caught between said rest and said pulling means.

45 In testimony whereof I have signed my name to this specification.

GEORGE GODDU.
